(57) **CLAIM**

The ornamental design for a financial apparatus, as shown and described.

DESCRIPTION

FIG. 1 is an exploded top, front, and right side perspective view of a financial apparatus, showing my design;

FIG. 2 is a top, front, and right side perspective thereof, showing one panel in an assembled configuration;

FIG. 3 is a top, front, and right side perspective thereof, showing two panels in an assembled configuration;

FIG. 4 is a top, front, and right side perspective thereof, showing three panels in an assembled configuration;

FIG. 5 is a top, front, and right side perspective thereof, showing four panels in an assembled configuration;

FIG. 6 is an enlarged perspective view of an encircled portion "6," in FIG. 1;

FIG. 7 is an enlarged perspective view of an encircled portion "7," in FIG. 1;

FIG. 8 is an enlarged perspective view of an encircled portion "8," in FIG. 1; and,

FIG. 9 is an enlarged perspective view of an encircled portion "9," in FIG. 2.

The even dashed broken lines shown of the representations of the U.S. penny coin shown in FIGS. 1, 5, and 6; of the representations of the U.S. dime coin shown in FIGS. 1, 4, 5, and 7; of the U.S. nickel coin shown in FIGS. 1, 3, 4, 5, and 8; and of the U.S. quarter coin shown in FIGS. 1-5, and 9; represent portions of the financial apparatus, that form no part of the claimed design. The even dashed broken lines shown in the drawings represent portions of the financial apparatus, that form no part of the claimed design.

The dot-dashed broken lines illustrate the boundary lines of the enlarged portion views and form no part of the claimed design.
